UNITED STATES PATENT OFFICE.

WILLIAM WISHART AND JOHN O. WISHART, OF CLINTON, IOWA, ASSIGNEES TO
CLINTON REFRIGERATING COMPANY, OF CLINTON, IOWA, A CORPORATION OF
IOWA.

REMOVABLE CROSSHEAD FOR COMPRESSORS.

Application filed February 26, 1918. Serial No. 219,218.

To all whom it may concern:

Be it known that we, WILLIAM WISHART and JOHN O. WISHART, citizens of the United States, and residents of the city of Clinton, in the county of Clinton and State of Iowa, have invented certain new and useful Improvements in a Removable Cross-Head for Compressors; and we do hereby declare that the following is a full, clear, and exact description of the same, reference being had to the accompanying drawings, and to the numerals of reference marked thereon, which form a part of this specification.

Our invention relates to compressors for refrigerating and similar machines, and has for its object to provide certain improvements in the construction of cross head for rotating the same and its connected parts, as hereinafter more definitely will be pointed out and claimed, reference being had to the accompanying drawings, in which:—

Figure 1 is a side view of a complete refrigerating plant constructed in accordance with our invention.

Figure 2 is an end view of the compressor.

Figure 3 is a side view of the compressor.

Figure 4 is an enlarged longitudinal vertical sectional view on the line 4—4 of Figure 2.

Figure 5 is an enlarged horizontal sectional view on the line 5—5 of Figure 3.

Figure 6 is a side view of the reciprocating member or double piston.

Figure 7 is an enlarged longitudinal sectional view of one end of the reciprocating member.

Figure 8 is an inner end view of the valve and valve holder provided at each end of the reciprocating member.

As shown in the drawings:

The reference numeral 1, indicates a refrigerator and may be of any suitable construction and has the expansion coil 2, in the top thereof which is adapted to be supplied with a fluid for reducing the temperature in the refrigerator. The reference numeral 3, indicates a hollow base which is adapted to contain the condenser coils 4, and be supplied with water through the pipe 5, which is circulated through the condenser chamber and discharged through the pipe 6, and adapted thereby to cool the refrigerating fluid in the coils 4. Mounted upon the base 3 is the compressor 7, com-

prising a pair of cylinders 8, arranged one 55 at each end of the crank case 9, and provided with a reciprocating member 10, having the ends thereof operating in the cylinders 8. The crank case 9, is adapted to serve as an inlet chamber for the fluid to 60 be compressed, which is supplied thereto through the pipe 11, which is connected through the valve 12, and scale remover 13, to the exhaust end of the expansion coil 2. Each end of the reciprocating member 10, 65 is hollow as shown in Figure 5, and has the valve 14, in the end thereof, which is slidably mounted in the hub 41, of the valve cage 42, which is threaded into the end of the piston. This valve is held closed by the 70 spring 43, compressed on the stem 44, between the hub 41 and head 45, and there is a spring 46, between the hub and valve 14, adapted to counterbalance to some extent the tension of the spring 43, to hold the valve 75 lightly closed and enable it to open readily. In the outer end of the cylinder there is a valve 15, similar to the valve shown in my application for compressor filed February 26th, 1918, Serial No. 219,210, which valve 80 is seated against an annular valve seat 47, formed around the outer end of the cylinder bore. This valve, which forms the end wall of the cylinder bore is slidably supported in a removable valve holder 48, which 85 is clamped in place by the cylinder head 49, which bears thereagainst. It will be observed that by reason of the end of the cylinder being entirely open and closed by the valve 15 the cylinder can be bored out from 90 the end, and the valve construction affords a simple means for effectively closing the end of the cylinder, which can be easily removed for repairs and to permit access to the cylinder.

At the inner end of the chamber 16, which is formed at each end of the reciprocating member are a plurality of radially arranged passages 17 which are adapted when the piston is at the end of its inward stroke to 100 afford communication between the chamber 16, in the piston and the chamber 18, in the crank case 7, and supply fluid from the chamber in the crank case through the piston to the chamber in the cylinder at the 105 outer end of the piston, to be compressed therein. A further means to insure complete filling of the cylinder chamber at the

outer end of the piston, consists of the grooves or channels 40, which are preferably arranged spirally in the inner surface of the cylinder bore, as shown by dotted lines in 5 Figure 4, which, when the piston is at the end of its inward movement, afford communication from the chamber 18, in the crank case to the cylinder chamber at the outer end of the piston. When the piston 10 starts to move outwardly it passes over the outer ends of these channels and interrupts communication.

At one side of the compressor, the crank case is closed by means of an integral wall 15 and the opposite side thereof is provided with an opening 19, which is closed by means of a cover plate 20, which is attached by means of the bolts 21, and has a central opening 22, for the drive shaft 23, whereby 20 the piston member 10, is reciprocated.

At the outer side of the plate 20, there is an outwardly extending sleeve 24, spaced from the shaft 23, so as to provide a packing chamber within which packing material 25 25, may be compressed to prevent leakage around the shaft 23. A bushing or insert 26, slips into the end of the sleeve 24, and the outer end thereof is engaged by the nut 27, having a threaded connection with the 30 sleeve 24, whereby the bushing may be forced into the sleeve to compress the packing.

The outer end of the drive shaft 23, is provided with a coupling 28, whereby the shaft may be connected to a rotary drive 35 member to apply power for operating the compressor.

The reciprocating member 10, may be of uniform diameter from end to end as shown and intermediate of the ends is slotted or 40 grooved transversely and has the channelled member 29, secured in the groove of the reciprocating member by means of screw 30. (See Fig. 5). This channelled member 29, serves as a cross head and has a block 31, 45 mounted therein to slide lengthwise of the channelled member 29, and adapted to have the crank pin 32, of the crank disk 33, journaled therein. This crank disk 33, is secured to the inner end of the shaft 23 so as to 50 turn therewith, and the block 31, may be provided with a removable bushing 34, to provide a bearing for the crank pin 32, which said bushing may be removed and replaced when it becomes worn.

55 At each end of the compressor is an outlet pipe 35, which connects through the pipe 36, with the condenser coil 4, and this coil is provided with an outlet pipe 37, which has the valve 38 and communicates with the inlet 60 end of the expansion coil 2, in the refrigerator.

The operation is as follows:

Power is imparted to the shaft 23, through the coupling 28, and causes rotation of the 65 crank disk 33, and crank pin 32, thereof. The

member 10, being confined to a reciprocal movement by reason of engagement with the walls of the cylinders 8, is reciprocated by the movement of the crank pin 32, and as the crank pin 32, revolves the up and down movement thereof is provided for and prevented from being applied to the reciprocating member 10, by reason of the sliding engagement of the block 31, in the grooved cross head 29. As one end of the reciprocating member 10 moves from the outer end 70 of the cylinder 8, inasmuch as the outer end of the cylinder is normally closed by means of the valve 15, a partial vacuum is formed in the cylinder chamber between the valve 80 15, and that end of the reciprocating member 10, which causes the valve 14, in the end of the reciprocating member to open and permit passage of the fluid to be compressed from the crank case 18, into the outer end 85 of the cylinder. The reverse movement of the reciprocating member 10, then draws in an additional amount of fluid to be compressed through the inlet pipe 11, from the expansion coils in the refrigerator, and at 90 the same time compresses the fluid in the cylinder chamber at the outer end of the piston. When the pressure of the compressed fluid in the cylinder chamber exceeds the pressure of the valve 15, said valve 95 is opened thereby and the fluid under compression in the cylinder chamber is forced out through the valve and the outlet pipes 35, 36 into the condenser coil 4, in the base 100 of the compressor. The compression of the fluid in the cylinder heats the fluid and as it passes through the condenser coil 4, the water circulating around the coil lowers the temperature of the fluid and reduces it to a suitable condition so that when it is discharged into the pipe 27, and into the expansion coil 2, it will expand and absorb 105 heat from the refrigerator and thereby reduce the temperature thereof.

Our improved construction provides an 110 extremely simple means for the removal of the piston for repairs as the unbolting of the plate 20 permits the removal thereof, together with the shaft 23, the disk 33 and its pin 32 as a unit. Then by removing the 115 single screw 30 the cross-head 29 may be removed through opening 19, leaving the piston free for removal through the end of either of the cylinders 8. And in like manner the parts readily may be assembled.

In order to prevent overheating of the compressor, a water jacket 38, is formed around the cylinder and crank case and water may be supplied thereto from the chamber in the base 3, through the pipe 6, 125 120 or from an independent source if desired.

While we have shown our invention in a certain specific form, for the purpose of illustration, we are aware that various changes and modifications may be made 130

without departing from the spirit of our invention, and we therefore do not purpose limiting the patent granted otherwise than necessitated by the prior art.

5 We claim as our invention:

1. The combination with a crank case having a side opening therein, of a piston reciprocal therein and slotted in one side, a channeled cross-head removably secured

10 transversely in said slot, a crank disk disposed in said crank case opening, a crank pin on said disk engaging a block slidable in said cross-head, a drive shaft fixed to said disk, and a cover plate removably attached 15 to said crank case over the side opening therein and serving to retain said crank disk in position.

2. The combination with a crank case having a side opening therein, of a piston reciprocal therein and slotted in one side, a channeled cross-head removably secured

transversely in said slot, a crank disk disposed in said crank case opening, a crank pin on said disk engaging a block slidable in said cross-head, a drive shaft fixed to said 25 disk, and a cover plate removably attached to said crank case over the side opening therein and serving to retain said crank disk in position, said plate being centrally apertured to receive the drive shaft there- 30 through and having an outwardly extending sleeve spaced from said shaft to form a packing chamber for said shaft.

In testimony whereof we have hereunto subscribed our names in the presence of two 35 subscribing witnesses.
